United States Patent Office.

ANDREW BARCLAY, OF KILMARNOCK, NORTH BRITAIN.

Letters Patent No. 62,993, dated March 19, 1867.

IMPROVEMENT IN INJECTORS FOR STEAM GENERATORS.

The Schedule referred to in these Letters Patent and making part of the same.

TO WHOM IT MAY CONCERN:

Be it known that I, ANDREW BARCLAY, of Kilmarnock, in the county of Ayr, North Britain, have invented certain new and useful improvements in Apparatus for Injecting or Ejecting Fluids or Liquids; and I hereby declare that the following is a full, clear, and exact description of the same.

This invention relates to certain improvements in apparatus used for the purposes of injecting and ejecting fluids and liquids, and consists chiefly in the arrangement of the steam and water nozzles as hereinafter described, and in the construction of the apparatus so as to admit of its being easily opened up, rendering the packing, stuffing-boxes, &c., around the steam passage, accessible and capable of being adjusted without necessitating the taking asunder of any parts of the instrument. Another improvement under this invention consists in forming a tapered or conical condenser, into which steam or other condensable vapor is admitted, in such quantity as may be required for the purpose of injecting or ejecting fluids. In this arrangement, the fluids injected or ejected have imparted to them the momentum of the fluid, moving with the velocity of the vapor used rushing into a vacuum. In this apparatus the condensation may be effected in any of the modes generally used for condensing steam or other vapors. These hereinbefore-mentioned arrangements are more clearly described in reference to sheet 1 of the accompanying drawings.

Description of Drawings, Sheet 1.

One modification of this improved apparatus is shown in vertical section in Figure 1. The cylindrical body of the apparatus may be all cast in one piece, but it is preferred to construct it of three separate parts, screwed or bolted together, as shown in fig. 1. The steam in this modification enters by the branch pipe A, the water or other fluid to be raised enters by the branch pipe B, and the overflow is formed by the branch pipe C, cast on the lower part of the apparatus, as also the flange D, which flange forms the connection to the boiler or other receiver, through which the fluid to be injected passes. The steam nozzle E is screwed into one end of the adjustable cylinder F, and is surrounded by an envelope or casing G, leaving a free space between the outside of the nozzle E and its casing G; this space may be filled with any non-conducting substance, or it may only contain the air enclosed in putting on the casing. The object of surrounding the steam nozzle with any non-conductor of heat is to maintain a high temperature of the steam until it reaches the exit from its nozzle E, as priming is very injurious whilst forming the vacuum. The water or second nozzle H, in this modification, is extended to a considerable distance beyond the first or steam nozzle E, and becomes of an annular form by the introduction of the centre adjustable spindle I. The tapered form of this spindle I, when raised or lowered, by turning the hand-wheel J, increases or diminishes the annular space, to suit the pressure of steam employed, and the height from which the water or other fluid has to be raised. At a short distance from the nozzle H, a receiving nozzle or throat, K, is so placed and adjusted by means of a self-acting valve, L, that when a greater or less quantity of fluid is discharged from the nozzle H, the throat accommodates itself accordingly. The adjustable cylinder F may be raised or lowered by turning the hand-wheel M, through the introduction of a screw formed on itself, working in a nut formed in the upper part of the apparatus, as shown at N, or any other convenient appliance, to obtain a similar effect, that is, the raising and lowering of the cylinder to suit the desired quantity of fluid to be injected. A series of holes or slots is formed opposite the steam branch A, through which the steam passes to the interior of the cylinder F, as indicated by the arrow at O. To maintain a perfectly air-tight packing between the steam branch A and the nozzle-chamber P, hemp or other elastic substance is forced into the space Q, between the adjustable cylinder F and the body of the apparatus, by means of a gland, R, which may either be screwed into the body of the apparatus itself, or by studs or bolts through flanges, as shown in figs. 1, 2, and 3. The cylindrical part of the gland R, within the body of the apparatus, and where it passes the steam branch A, has a series of holes or slots, so as to admit of a free passage of the steam to the interior of the adjustable cylinder F, and may be screwed up so as to compress the packing into the space Q, without in any way obstructing the steam passage. When the water or other liquid has to be raised about twenty or twenty-five feet, it is very necessary that the lower packing Q should be perfectly air-tight, and this can be accomplished at any time by screwing up the gland R, shown in figs. 1 and 2. To prevent any passage or leak of steam within and around the gland R, two stuffing-boxes with glands

S and T, are screwed up by means of bolts or studs when required. The adjustable spindle I is kept steam-tight by the stuffing-box U. The action of the apparatus may be described as follows:

On steam being admitted by the branch pipe A, it issues at the nozzle E, and on meeting the angle of the second nozzle H, it is deflected towards the centre spindle I, from which it is again deflected towards the nozzle H, in a zigzag form; this zigzag wave motion expels the air from the nozzle-chamber P, and the steam, forming, as it were, an annular fluid piston, prevents any return through the nozzle H. So soon as the vacuum is sufficient to raise the water or other fluid to be injected, it rushes in through the branch pipe B, and is expelled by the steam through the second nozzle H, the water and steam together now forming the fluid piston in the nozzle H. The water as yet may not have sufficient force to pass through the throat K; it therefore gets an outlet by the overflow passage G. On turning the hand-wheels J and M, so as to give both more water and steam, the force imparted to the water becomes sufficient to pass through the throat K, and enter the boiler or other receiver. In starting the apparatus it is very essential that steam nozzle E should be very close to the second nozzle H, when the water has to be raised from a great depth, such as twenty-five feet or thereabouts.

Another modification of packing the adjustable cylinder F is represented in Figure 4. In this arrangement one gland, R, serves to maintain the adjustable cylinder F perfectly steam and air-tight. Around the loose ring or cylinder V, and through it, are a series of holes or slots, opposite the steam branch A, to admit of the steam passing to the interior of the adjustable cylinder.

In another modification, with the steam and water branches reversed, as in Figure 5, the steam for the first impulse strikes against the centre spindle I, and is deflected towards the nozzle H, as shown by the dotted lines in fig. 5; otherwise the action and construction of the apparatus are similar to those just described. The water passing through the nozzle E is expelled through the nozzle H by the surrounding annulus of steam, and gains sufficient force to pass through the throat K into the receiver, where water or other fluids are required.

It will be observed from the foregoing description that water may be raised from a great depth and fed into a steam boiler or other receiver direct by the aforementioned apparatus.

At Figure 6 is shown in vertical section another modification of my improved apparatus for injecting and ejecting fluids and liquids. The peculiarity of this arrangement is, that in it there are two streams of water admitted, one through the branch A, and another through the branch B, whilst the steam is admitted through the branch C, and on issuing from the nozzles, it will be seen, on referring to the drawings, that the jet of steam is enclosed or confined between the two jets of water issuing from the nozzles, and being conducted thence by the passages D and E, leading from the branch inlets A and B respectively. In this arrangement it will be observed that the body of the instrument is opened up so as to gain access from the exterior to the several gland flanges F G H and I, by which the several joints are kept steam-tight and water-tight. From the body of the upper part of the instrument a broad flanch K projects, into which the studs L are firmly secured; the lower end of these studs passing into, and united to, a similar flanch in the lower body part of the apparatus. Between the upper and lower body parts of the instrument the intermediate part M is introduced, which carries the outer set of nozzles. At one side of the upper end of this intermediate part a lug, N, projects, into which a screw-thread is cut for the reception of the screw O, by turning which in either a right or left-hand direction the outer nozzles are adjusted. The inner nozzle is adjusted by actuating the hand-wheel P, with the tubular part Q, which carries it; this tubular part turning in the screwed portion R of the outer part of the instrument. The central spindle S is adjusted as in the preceding modifications.

Having pointed out in detail the most important parts of this modification of my said invention, I shall now proceed to show the distinctive features and peculiarities of this arrangement to be, as follows, that is to say, in this modification there are two water inlets or branches, A and B, in lieu of one as used in the former modifications, whilst there is only one inlet for steam, the two water branches A and B being in direct communication with the two annular nozzles. When it is desired to feed a fluid of a somewhat elevated temperature, the warmed fluid is admitted through the branch A, whence it travels or passes onwards to the central water space, but since the principle of the apparatus and its effectual working are chiefly dependent upon the formation of a vacuum produced by the condensation of steam admitted at the branch B, it is obvious that if the injected or ejected fluid be of a very elevated temperature, it will act detrimentally upon the working of the instrument by preventing so perfect a vacuum being formed. To counteract the production of this effect, and to secure the very effectual working of the instrument prior to the admission of the heated fluid, a colder fluid, or one possessed of a temperature sufficiently low to insure the action being effective, is first admitted through the branch B, and this coming in contact with the steam jet, causes the latter to be speedily condensed, when the cold water is impelled forward with a velocity corresponding to that of the pressure of steam used, rushing from an orifice into the atmosphere, the impelled water having a momentum equivalent to its own weight multiplied by the velocity of the flow of the steam or other impelling fluid. So soon as the action of the instrument is insured by the admission of the cold water and steam, then the heated liquid is admitted, and it is, as it were, pulled forward through the nozzle by the rushing action of the colder fluid.

Another form of injecting or ejecting apparatus is shown in vertical section at Figure 7, which consists simply of an outer casing, A, into which a current of cold water or other fluid of low temperature is admitted by the branch B, and out of which it flows by the duct C. The use of these two branches, B and C, is to provide the means to enable a continuous flow of cold fluid around the conical nozzle D, into which steam is admitted and condensed.

When the condensation has taken place, a continuous rush of steam from the source of that fluid impinges upon the condensed portion and causes it to be emitted from the nozzle with a momentum corresponding to the amount of condensed steam multiplied into the velocity with which the steam itself would push into a vacuum.

Figure 8 is a modification of this last-named apparatus, in which the whole, or a portion, of the condensing

fluid is ejected, as well as the condensed fluid itself; this result being effected by making the nozzle to terminate a short distance within the vessel containing the condensing fluid.

Another improvement under this invention consists as follows: The portion of the apparatus which contains the steam and water nozzles is furnished, at the end nearest the handles or wheels for regulating the flow of the water and steam, with a flanch, into which four or other number of pillars are fixed, being arranged to carry, at their upper ends, another similar flanch, which projects from and forms part of a tube; one portion of which extends downwards into the main body of the instrument, leaving an annular space around it, whilst the other portion above the flanch has a screw-thread formed on it, which is used, as will hereinafter be shown, for partly regulating the feed. The main portion of the instrument has a stuffing-box formed in it, and is provided with a gland, through which passes a tubular piece, carrying at its inner end the steam nozzle. This last-mentioned tubular piece is furnished at its outer end with a flanch, into which two or more pillars are fixed; these carry, at their upper end, a ring, which fits into a circular recess formed on the regulating wheel or handle, and by turning the wheel or handle upon the screwed portion of the first-mentioned tubular piece, the steam nozzles are caused either to recede or advance. It should be mentioned that the tube carrying the steam nozzle fits into and is capable of being moved upwards or downwards in the annular space formed by the first-named tube and the body of the instrument. Two of the pillars of the lower set and the two forming the upper set are screwed so that nuts may pass over them for tightening the glands of the stuffing-boxes which surround both the first and second-named tubular pieces. As it is desirable to have as much command as possible over the quantity of feed at any given time, to further this object, the spindle by which the flow of the steam from the nozzles is regulated is, under the present invention, made hollow, and a solid spindle is passed down through the opening. By means of this arrangement the inner spindle is regulated to give any desired amount of opening for the flow of the water, and is made to pass down into the water nozzle for the purpose of enlarging or contracting the area of the opening. By moving the outer ring the flow of the steam can be varied or shut off as required. The hollow spindle passes through a stuffing-box in the upper end of the screwed tubular piece. Another peculiar feature of this invention consists in forming the valve in the throat of the apparatus of such a curved form that by means of this form and the back pressure of the feed water, its area of opening is made to exactly correspond at any time with the area of opening of the water nozzle.

There are other modes of varying the actual area of the nozzles besides the one hereinbefore referred to, viz: An air-tight box may be cast on one side of the body of the apparatus, having in it a spindle, equal portions of which have right-and-left screw-threads cut on them. The spindle passes through two pieces of metal of a quadrantal form, in which a set of nozzles of various sizes is fixed, the use of the right and left-hand screw being that when it is required to shift the quadrantal piece, by turning the spindle in one direction these pieces are released from the actual nozzle and throat of the instrument, so that it can be turned on its centre until a set of holes, which will give the required feed, is brought round, when the spindle is reversed, and the quadrantal pieces are again brought close against the nozzle and throat, in manner suitable for working. Besides the last-mentioned arrangement, a cock may be made to revolve, having holes or nozzles made in it of different sizes, to correspond with variations of feed, the holes or nozzles being turned round to suit the feed required. The improved arrangements just referred to will be clearly understood from the description of the drawings, sheets 2 and 3, immediately following.

Description of Drawings, Sheets 2 and 3.

On Sheet 2, Figure 1, is a longitudinal section of the improved injecting and ejecting apparatus. Figure 2 is a similar section of another form of the apparatus.

In fig. 1 the lower part of the body of the instrument is composed of three principal pieces, A A¹ A², which are screwed together in the manner shown. The upper end of this part of the instrument is furnished with a flanch B, which carries the four pillars C, two only of which are seen at fig. 1. The four pillars C carry at their upper end the flanch D, and from the upper and lower sides of this flanch the tubular pieces E and E' project, the upper one having a square threaded screw formed thereon, as seen in the figure. The hand-wheel F, for regulating the opening of the water nozzles, has a screw-thread cut in it to correspond with that on the tubular piece E', and the boss of the wheel projects below to receive a flanch, G, which is kept in place on the boss by means of the collar H. From this flanch G, two pillars, I, pass downwards, through holes in the flanch D, and are thence continued on to the flanch K, which carries the tubular piece L and nozzle L', by means of which the supply of water is regulated. As it is necessary that the joint between the tubular piece L and the external body part A, should be air-tight, a stuffing-box is provided at the upper end of the piece A, and a gland M, having holes, through which the pillars C pass, keeps the packing tight therein, the pressure on the gland being regulated by the nuts on the screwed portions of the pillars. By means of this arrangement, the great difficulty always hitherto experienced in keeping tight the bottom packing of the tube carrying the water nozzles is obviated, as the packing in the stuffing-box can at any time be instantly tightened up, or, if required, new packing may be rapidly filled in, so that the inaccuracies of the working of the instrument on account of a leaky joint at this part are prevented, and its continuous action is now rendered certain for any length of time. It is absolutely necessary, when apparatus of this class is employed for lifting liquids from great depths, that the joint around the steam passage E, formed by the stuffing-box and gland M, fig. 1, should be maintained perfectly air-tight, otherwise the lifting efficiency of the instrument is much impaired by air passing in around the steam passage, and mixing with the water as it passes towards the nozzles L, through the passage V, and as the apparatus, as arranged in the several modifications comprised under this invention, is more especially designed with the view of lifting liquids from much greater depths than hitherto, the opening up of the outside body parts of the instrument so that the packing around the steam passage may be instantly adjusted without

the necessity of taking any part of the instrument asunder, is considered the special feature and main improvement, as comprised under these present Letters Patent. It is to be understood that the remarks in this immediately preceding clause apply equally to the three succeeding modifications hereinafter specified. The admission of steam through the nozzles is, in this modification, regulated in the usual manner by means of a central spindle O', the screwed part of which passes through a hole correspondingly cut in the inner projection O² of the tubes E E'. The steam inlet is indicated by the dotted circular lines W. V is the water inlet, and X the overflow; Y being the valve by which direct communication with the boiler is prevented when the instrument is not feeding.

In Figure 2, sheet 2, the general arrangement is much the same as that described and shown in reference to the preceding modification, and the same figures or letters of reference are affixed to parts corresponding to those in fig. 1, and therefore need not be further referred to.

The chief peculiarity in this second modification consists in so arranging the instrument that the regulating wheel F, together with the screw arrangement, flanch G, and pillars I, constituting the gear by which the admission of water is regulated, are dispensed with. A three-sided flanch, M, is formed on the tubular piece, fig. 2; and the part A of the body of the instrument is provided with a corresponding flanch; the two parts are connected together by studs C. A stuffing-box is formed in the upper part of the tubular piece A, and the gland N secures the packing therein, forming a perfectly tight joint around the pieces O, being pressed down by nuts in the usual manner. The piece O, carrying the water nozzle L, is regulated by means of the screw P, which turns in a lug, P', cast on one side of the piece O. A stuffing-box is also formed at the upper part of the piece O, by which a perfect joint is maintained between it and the inner tubular piece O', through which the steam passes on to the nozzles. The central spindle Q, by which the admission of steam is regulated, is adjusted in the usual manner by means of the screw R, the spindle passing through a stuffing-box, S, and surmounted by a hand-wheel, T, by which it is actuated. The advantages resulting from this second modification are similar to those previously described and referred to as belonging to the first arrangement.

On sheet 3, Figure 1, is a longitudinal section of another modification of my invention. In this arrangement the lower part of the instrument is also made of three parts, A A¹ and A², as in the first modification referred to, on sheet 2 of the drawings, and the upper part, A³, is furnished with a flanch for carrying the pillars B, by which the upper and lower exterior or main parts of the instrument are connected. In order to obtain easy access to the packing of the inner tube C, with the view of rendering the joints between it and the outer parts of the instrument more firm and secure, stuffing-boxes D and D' are formed in the upper and lower exterior portions, and glands E and E' are respectively provided to keep the packing tight, the pillars B having screw-threads cut on them, and provided with nuts, as shown in the figure, by which the tightness of the joints is regulated. By means of this mode of arranging these parts of the instrument, the packing around the tube C is easily accessible, so that the joints may be continuously maintained tight, and the admission of the air with the water as it is drawn or forced in through the supply passage F, as well as the escape of steam around the tube C, as this is let in for producing the feeding action, is prevented.

Figure 2 shows in horizontal section the passages in the tube C by which the steam is admitted on its way to the nozzles. For regulating the supply of water, the tube C is furnished with a hand-wheel, F, by which the tube is turned in its screw-bearing, G, formed in the upper main portion of the instrument. The central spindle H, for regulating the flow of steam through the nozzles, is also operated in manner similar to that shown and described in reference to the two previous modifications, and as all the other parts of the apparatus not described in reference to this modification are similar to those shown in the two previous modifications, and are common to apparatus of this class, it is not considered in the present case necessary to refer to them.

Figure 3, sheet 3, represents another modification of the apparatus. In this case the general arrangement is much the same as that shown in the modification immediately preceding, with the exception that in place of regulating the admission of water by means of a hand-wheel on the tube C, in this case it is regulated by the screw I passing through the upper and lower flanches A² and A³, respectively; a collar, K, being placed on its lower end to prevent its position with respect to these flanches being altered. A lug, L, is cast on one side of the tubular piece C, and the screw I passes through a corresponding screw-threaded hole cut therein, so that as the screw I is turned either in a right or left-hand direction the tube C and the water nozzles L' are accordingly raised or lowered. In both figures 1 and 3, sheet 3, M is the steam nozzle, N the water nozzle, and O the overflow. As shown in all the modifications on sheets 2 and 3, I prefer to employ the hollow nozzles, described in reference to sheet 1 of the accompanying drawings. The nozzle is constructed by means of the cavity in the outer piece a being made of larger diameter than the outer diameter of the inner piece b, so that a space shown by the darkly shaded parts in figs. 1 and 2, sheet 2, and figs. 1 and 3, sheet 3, is left between them; this space may be allowed to remain as an air space, or may be filled with non-conducting material, as hereinbefore described in reference to sheet 1 of the drawings.

At Figure 4, sheet 3, is shown one mode of arranging and applying a variable set of nozzles. In this arrangement a parallel cylindrical opening is made right through the body of the instrument, at that part wherein the nozzles c and throat d of the instrument are situated. A tubular piece A, having a set of nozzles, a, of various sizes, and throat pieces b, corresponding to them, are fixed on opposite sides of this tubular piece, and as the ends of the actual nozzles c and throat d are constructed to correspond and fit against the exterior surface of the tubular piece A, any one of the various nozzles and throats, situated in this piece A, may at once be applied by sliding the piece A through opening until the nozzle and throat necessary for producing the required feed are brought into position to enable the instrument to work.

Instead of constructing the variable nozzles, and using the mode of applying them, as shown at fig. 4,

sheet 2, they may be constructed of two quadrantal or circularly formed pieces, as described in an earlier part of this specification. What I consider specially as my invention at this point is the application of a variable set of nozzles and throats to apparatus of the class to which these present Letters Patent refer.

Claims.

1. The combination, with the steam and water nozzles of an injector, of a fixed casing, containing any non-conducting substance, interposed between the said nozzles, as herein shown and specified.
2. The arrangement of an adjustable air-tight packing between the steam and water inlets, as hereinbefore described.
3. The arrangement and construction of apparatus for injecting or ejecting fluids and liquids, in which a double set of nozzles is employed in combination with an injecting or water nozzle, so as to form annular jets of steam and water, as hereinbefore described.
4. The arrangement and construction of apparatus for injecting or ejecting fluids of different temperatures, whether in immediate contact or not with the steam nozzle, as hereinbefore described.
5. The combination of the exterior main portions of the instrument, with the pillars or studs, or equivalent devices, for connecting the same under the arrangement herein specified, so that the stuffing-boxes, joints, and packing are rendered accessible, and capable of being readily adjusted, as set forth.
6. The application of a set of variable nozzles and throats to apparatus of the kind hereinbefore described, in the manner specified.

In testimony whereof I have signed my name to this specification in the presence of two subscribing witnesses.

ANDREW BARCLAY.
